US00D995327S

(12) **United States Design Patent** (10) **Patent No.:** **US D995,327 S**
(45) **Date of Patent:** **** Aug. 15, 2023**

(54) **DIGITAL LEVEL**

(71) Applicant: **Milwaukee Electric Tool Corporation**,
Brookfield, WI (US)

(72) Inventors: **Eric Mackey**, Milwaukee, WI (US);
Matthew Leidel, Wind Lake, WI (US)

(73) Assignee: **Milwaukee Electric Tool Corporation**,
Brookfield, WI (US)

(**) Term: **15 Years**

(21) Appl. No.: **29/824,340**

(22) Filed: **Jan. 24, 2022**

Related U.S. Application Data

(57) **CLAIM**

We claim the ornamental design for a digital level, as shown and described.

DESCRIPTION

FIG. 1 is a perspective view from above of an embodiment of the claimed design;

FIG. 2 is a perspective view from below of the claimed design of FIG. 1;

FIG. 3 is a front view of the claimed design of FIG. 1;

FIG. 4 is a back view of the claimed design of FIG. 1;

FIG. 5 is a top view of the claimed design of FIG. 1;

FIG. 6 is a bottom view of the claimed design of FIG. 1;

FIG. 7 is a right view of the claimed design of FIG. 1;

FIG. 8 is a left view of the claimed design of FIG. 1;

FIG. 9 is a perspective view from above of an embodiment of the claimed design;

FIG. 10 is a perspective view from below of the claimed design of FIG. 9;

FIG. 11 is a front view of the claimed design of FIG. 9;

FIG. 12 is a back view of the claimed design of FIG. 9;

FIG. 13 is a top view of the claimed design of FIG. 9;

FIG. 14 is a bottom view of the claimed design of FIG. 9;

FIG. 15 is a right view of the claimed design of FIG. 9; and,

FIG. 16 is a left view of the claimed design of FIG. 9.

The ornamental design which is claimed is shown in solid lines in the drawings.
